UNITED STATES PATENT OFFICE.

SAMUEL W. WILSON, OF NEW YORK, ASSIGNOR TO WILLIAM S. EARL AND GARDNER EARL, OF TROY, AND WASHINGTON WILSON, OF NEW YORK, N. Y.

CUFF.

SPECIFICATION forming part of Letters Patent No. 234,361, dated November 9, 1880.

Application filed June 5, 1880. (No model.)

To all whom it may concern:

Be it known that I, SAMUEL W. WILSON, of the city, county, and State of New York, have invented certain new and useful Improvements in Cuffs, of which the following is a specification.

My invention relates to the detachable cuffs which are commonly worn by men and women.

The object of my invention is to so construct a cuff that it may by reversal be made to present a different appearance.

I am well aware that cuffs designed to be reversed end for end have been provided at one end with corners different from the corners at the other end.

My invention consists in a cuff having corners longitudinally opposite of different configurations, and adapted and designed to be lapped and secured with one corner only visible, so that the corners may be differently lapped to present the appearance of different cuffs.

It also consists in a detachable and reversible cuff having its longitudinally opposite corners at one end of different configurations, and adapted and designed to be lapped and secured with one corner only visible, so that the corners may be differently lapped to present the appearance of different cuffs, and having the corners at its opposite end different in configuration from those first named.

In the accompanying drawings, Figures 1 and 2 are plan views of two cuffs, forming a pair, embodying my invention; and Figs. 3, 4, 5, and 6 are perspective views of one of the cuffs with its corners differently lapped and its ends reversed.

Similar letters of reference designate corresponding parts in all the figures.

The cuffs may be of ordinary or other suitable materials and construction, except as regards the configuration of the corners. One corner, A, may have a long curve, another corner, B, may have a short or abrupt curve, another corner, C, may be cut off obliquely, and the remaining corner, D, may be square.

It will be seen that the corners longitudinally opposite at each end are of a different configuration, and that provision is thus af-

firmed for changing the appearance of the cuff by merely lapping the opposite corners either over the other. By also reversing the cuff end for end and lapping the corners at the end presented to view more changes in the appearance of the cuff will be made.

In Fig. 3, the corner A, having the long curve, is outermost and presented to view when the cuff is in use; in Fig. 4 the abruptly rounded corner B is outermost and will be presented to view; in Fig. 5 the oblique corner C is outermost and will be exposed to view, and in Fig. 6 the square corner D is outermost and will be visible.

It will be noticed, on reference to Figs. 1 and 2, that the cuffs of a pair are reversely formed, so as to be rights and lefts. This is necessary in order that when reversed they may be worn in corresponding positions on both wrists.

It will be seen that by my invention I provide for varying the appearance of cuffs a great deal to suit the taste or caprice of the wearer, and without adding to the cost of or in any way impairing the cuffs.

What I claim as my invention, and desire to secure by Letters Patent, is—

1. A cuff having longitudinally opposite corners of different configurations, and adapted and designed to be lapped and secured with one corner only visible, so that the corners may be differently lapped to present the appearance of different cuffs, substantially as specified.

2. A detachable and reversible cuff having its longitudinally opposite corners at one end of different configurations, and adapted and designed to be lapped and secured with one corner only visible, so that the corners may be differently lapped to present the appearance of different cuffs, and having at its opposite end corners different in configuration from those first named, substantially as specified.

SAM'L. W. WILSON.
